Attorney

UNITED STATES PATENT OFFICE.

JOHN MARTINSON, OF DULUTH, MINNESOTA.

PULLING MACHINE.

Application filed May 22, 1922. Serial No. 562,572.

To all whom it may concern:

Be it known that I, JOHN MARTINSON, a citizen of the United States, residing at Duluth, in the county of St. Louis and State 5 of Minnesota, have invented certain new and useful Improvements in Pulling Machines, of which the following is a specification, reference being had therein to the accompanying drawing.

10 This invention relates to pulling machines and has special reference to one particularly designed for the pulling of stumps.

The principal object is to provide a stump puller of as light and convenient a structure 15 as possible in keeping with the maximum strength of the machine and one that may be conveniently transported from place to place manually.

Other objects and advantages of the invention will appear in the further description thereof.

Referring to the accompanying drawings forming part of this application in which like reference characters indicate like parts:

25 Figure 1 is a side elevation of a completely assembled puller embodying the invention,

Figure 2 is a top plan view of the same, and

Figure 3 is a vertical sectional view 30 through the winding drum shaft.

The device comprises a portable structure designed to be conveniently moved about from place to place by hand, it being preferably supported upon three wheels somewhat 35 in the form of a wheelbarrow, except that the rearmost wheels 4 are of castor-like form so as to readily accommodate themselves to the lateral as well as forward draft of the machine; the front wheel 5 being much 40 larger and of any desired construction.

The main body portion is preferably of cast metal and comprises the generally V-shaped horizontally disposed portion 1, within the rearmost spaced ends of which is 45 securely bolted the upright inverted U-shaped leg portion 2, the uniting bolts or rivets thereof being shown at 3. This leg portion 2 is preferably slightly inclined as shown in the drawing, the uppermost end 50 being forward of the lower terminations, and the upper end extends approximately one-half the distance above the body portion 2 that the legs extend below the same.

A shaft 6 extends transverse the rearmost 55 end of the body portion and union with the leg portion, the same being freely rotatable

within and projecting beyond the sides of the machine for optional engagement by any form of suitable crank for operating by hand, or other power imparting device.

The extreme forward end of the body portion 1 terminates in an engaging loop 7 in which a hook 9 may be engaged for assistance in transporting the machine, or for the end of the pulling line when a snatch 60 block is being used. Just back of said loop a depending arm 8 is attached in any desired manner and in the lower end of which is pivotally mounted the forward wheel 5, as at 10. Upon the opposite side of the 65 wheel 5 is a double depending member 11, it being of U-shape and attached as with the bolt 12, the lower spaced terminations being mounted upon the axle 10 of the wheel 5, intermediate of the latter and one of the 70 handles 13. The double member 11 acts as a side support for the wheel and handles opposite to the depending member 8 as well as a support for the two rollers or sheaves 14 and 15, intermediate of which the pulling 75 line 16 is payed, which when drawn taut in the act of pulling tends to raise the front end of the puller from the ground.

There are two handles 13 their free manually engaged ends being spaced sufficiently 80 far apart to provide easy manipulation.

About the shaft 6 at the rear of the device is mounted a combined worm wheel and drum, the worm being indicated at 17 and the drum at 18. This forms the pulling 85 drum about which the line 16 is payed, usually three or four turns, the free end being led out forwardly of the machine parallel with the incoming portion of the line through automatically controlled means 90 hereinafter described. The free end of the line is shown at 19, the pulling portion of the line being indicated at 16. This combination drum and worm wheel is loosely 95 mounted about the crank shaft 6, and, adjacent one end of the latter, a spur gear or pinion 20 is fixed to said shaft, it meshing with the larger gear 21 fixed upon the crank shaft 22 spaced forwardly of the shaft 6 and rotatable within the body portion 1. Centrally upon the shaft 22 is fixed a beveled gear 23 meshing with a like beveled gear 24 on the inclined worm shaft 25 which is rotatably carried within the inclined inverted U-shaped frame 26 which is pivotally mounted 100 upon the shaft 22 upon either side of the gear 23. Upon the shaft 25 and within the 105 gear 23.

frame 26 is mounted the worm 27 which normally meshes with the worm wheel 17 and imparts motion and power thereto when the worm is driven by the rotation of the 5 shaft 22.

The upper end of the frame 26 is rounded or provided with a hub like projection 28 which is engaged within the keeper 29 pivoted at 30 within suitable brackets 31 extending upwardly from the upper end of the leg portion 2. The free end of this keeper is held normally in engagement with the upper end of the frame 26 by the contractile spring controlled rod 60 the upper end being 10 attached at 32 to the free end of the keeper and the lower end hooked about the smaller shaft 33 which is rotatably mounted within upstanding brackets 34 one upon either side of the body portion 1 and in close juxtaposition to the shaft 22. When quick disengagement of the worm from the wheel is desired it is seen that the free end of the frame 26 may be raised and tipped forwardly on its pivotal support which is the 15 shaft 22 after first moving in the opposite direction the free end of the keeper 29 so as to free the upper end of the frame 26 and when the frame 26 is held in this raised position and the keeper allowed to assume its 20 normal position the hub portion 28 of the frame 26 will be above the projecting lug 35 on said keeper and the worm thus held from engagement with the worm wheel during such times for example as the 25 unwinding of the pulling line or the initial placing of same about the drum 18. For reengaging the worm with the wheel all that is necessary is to raise the free end of the keeper 29 when the worm will drop back 30 into cooperative position with the worm wheel and the keeper assume its functioning 35 position automatically by the action of the spring rod 60 when released.

One end of the small shaft 33 is free to 40 raise and lower it being mounted within a slotted bearing 36 in one of the brackets 34 and upon the upper end of this bracket is pivotally mounted as at 37 a friction lever 38 which straddles the upper end of the bracket 34, and its free end is held 45 downwardly by the contractile spring rod 39, the lower end of which is hooked into one of a number of suitable holes in the up- 50 standing web of the body portion 1. This is for the purpose of keeping a downward 55 stress upon this end of the shaft adjacent which and in close proximity to one arm of the frame 26 is mounted a combined gear wheel and sheave, the gear portion of which 60 is indicated at 40 and the sheave at 41. This combined gear and sheave is loosely mounted 65 upon the shaft 33, and, directly below same, meshing therewith and loosely mounted upon the shaft 22, is a similar 70 combined gear wheel and sheave, the gear

portion of which is indicated at 42 and the sheave at 43. To the outer side of the gear 42 is rigidly fixed a sprocket wheel 44 rotated by means of a sprocket chain 45 leading to a somewhat larger sprocket wheel 46 70 rigidly fixed to the hub 55 of the drum 18 in any desired manner so that, as the drum 18 revolves, the two combination gear and sheave members will be rotated simultaneously therewith. The ratio of speed of 75 the tension sheaves to that of the drum is such as to constantly maintain tension upon the line intermediate of the sheaves and the drum as it is wound off of the latter, and this being essential in the successful 80 operation of the machine, these sheaves are preferably so speeded as to constantly tend to slip slightly on the line as they pull same. These combination gear and sheave 85 members are for the reception of the free end 19 of the line therebetween, the same being in frictional contact simultaneously 90 with both sheaves, said contact being constantly maintained by the bearing down of the lever 38 upon the shaft 33, as previously described. When the free end of the pulling line is thus constantly kept taut as it unwinds from the drum 18, a constant stress upon the line is secured during 95 the winding operation.

In the mounting of the combined drum and worm wheel 17-18, and associated parts, upon the shaft 6, it is to be understood that they are not directly mounted upon the shaft, as said shaft is surrounded by a tubular member or sleeve 56 which reaches entirely through the frame portion of the machine. To one end of the shaft 6 is keyed the spur gear 20, previously described, and, to the other end of the shaft 100 is fixed the collar 47, for preventing dislodgment of the shaft 6 in respect to the frame structure, as the hub connection with the body portion 1 is illustrated at 48 and a like connection with the U-shaped leg member 2 is illustrated at 49.

The anchorage bridle of the machine is illustrated at 50 it having spaced innermost ends which terminate in hub like portions indicated at 51, the same being mounted 115 upon the sleeve 56 as is the other of the pulling members. The anchorage line is shown at 52.

Thus it is evident that the stress of the 120 pulling line is brought upon the sleeve or tube 46 in preference to the shaft 6, the latter being free to rotate within said sleeve and perform its function independently thereof.

From the foregoing it will be apparent 125 that I have devised a very simple and convenient pulling machine, and one in which a pulling line of any desired length may be used as it passes continuously to and from the drum without being wound up thereon;

this being a great advantage in pulling a plurality of objects at different distances from the machine with one setting thereof.

Having thus described my invention, 5 what I claim as new and desire to secure by Letters Patent, is:

1. A portable pulling machine of the character described including a frame structure, two spaced rotatable shafts within 10 said structure, a line pulling drum mounted about one of the shafts, a worm wheel for driving said drum and concentric therewith, a worm pivotally mounted upon the other shaft and cooperatively engaged with 15 the worm wheel, means intermediate of the two shafts whereby the operation of one operates the other, means intermediate of the second mentioned shaft and the worm whereby power and motion is imparted 20 from said shaft to the worm, and an anchoring attachment, substantially as described.

2. A pulling machine of the character described comprising in combination a vehicle, a winding drum mounted within 25 the chassis of the vehicle, a worm wheel rigidly fixed to one end of the winding drum, a power shaft axially supported through the drum and rotatable independently thereof, a counter shaft spaced horizontally 30 from the power shaft and within the chassis, means whereby the counter shaft is operable simultaneously with the power shaft, an obliquely disposed worm

pivotally mounted on the counter shaft and engageable with the worm wheel on the power shaft, said worm being optionally engageable with said worm wheel, and an anchoring attachment, substantially as described.

3. A pulling machine of the character 40 described comprising in combination a vehicle, a winding drum mounted within the chassis of the vehicle, a worm wheel rigidly fixed to one end of the winding drum, a power shaft axially supported through the drum and rotatable independently thereof 45 a counter shaft spaced horizontally from the power shaft and within the chassis, means whereby the counter-shaft is operable simultaneously with the power shaft, an 50 obliquely disposed worm pivotally mounted on the counter shaft and engageable with the worm wheel on the power shaft, said worm being optionally engageable with said worm wheel, an anchoring attachment 55 adjacent said drum, a line leading from the drum forwardly through said vehicle, and means at the forward end of the vehicle for guiding said line.

In testimony whereof I hereunto affix my 60 signature in the presence of two witnesses.

JOHN MARTINSON.
